Att. 11

Philo C. Curtis
Letter's Patent

The Schedule referred to in these Letters Patent and making part of the same containing a description in the words of the said Philo C. Curtis himself of his improvement in the construction of a pump for raising water and other liquids.

To all to whom these presents shall come.

Be it known that I Philo C. Curtis of Utica in the County of Oneida and State of New York have invented a new and useful improvement in the construction of pumps for raising water or other liquids and that the following is a full and exact description of the construction and operation of the said machine as invented and improved by me. I form a cylinder, ^{similar} to those in use for common air or water pumps proportioned in size to the quantity of water or other liquid to be raised I furnish the bottom of the Cylinder with two valves one opening upwards and the other downward, the piston may be made wholly of metal or for packing in the ordinary manner the lever for working the pump is connected to the piston by a rod which is inserted in a mortise in the piston it is also secured in the lever by a pin in such manner as to form a joint the lever is supported at one end by a stand on the same platform that supports the pump or as may be most convenient I fasten a tube over the valve that opens downward which tube extends from the pump to a vessel made either of wood or metal which is placed in the fountain from which it is designed to raise water this is prepared with a valve on the inside at the bottom opening upward there is also another tube leading from near the bottom of

Dr. Wm. Green

said vessel to the pump or to any other place where the water is wanted, I insert a cock in the tube leading from the pump near the pump, the operation of this pump is similar to the common forcing pump with the exception that it is necessary to open the cock in the pipe and let the air escape from the vessel in the fountain and the water to enter when it must be again closed to continue the operation it will be most convenient in operating this pump to leave the cock open at all times after pumping by that means the vessel in the fountain will be full ^{of water} and afford the necessary quantity without waiting for it to fill. I design making the vessel of iron in the form of a globe to hold from four to six gallons for common use. The advantages to be obtained from the use of this pump are firstly the ease of raising water in consequence of a steady stream produced by the elasticity of the air. secondly its durability owing to its being worked with air instead of water. thirdly its being secure from frost as there is but a simple tube to convey the water which it is not necessary to provide with a valve in the bottom except in case of extreme length or height and lastly its neatness being well calculated for the use of families and for public houses for water beer &c. — What I claim as my improvement in the above described pump consists principally in arranging the parts in a form that water or other liquids can be raised advantageously without entering the body of the pump by means of a vessel as described above and tube leading to the — crane from the pump provided with a cock to enable the person working the pump to fill and discharge the vessel with air and water alternately. I also claim as my improvement the solid metal piston.
